UNITED STATES PATENT OFFICE.

FRIEDRICH VON MARTINI, OF FRAUENFELD, SWITZERLAND, ASSIGNOR, BY
MESNE ASSIGNMENTS, TO WILLIAM E. HALE, OF CHICAGO, ILLINOIS.

GAS-MOTOR.

SPECIFICATION forming part of Letters Patent No. 358,796, dated March 1, 1887.

Application filed November 27, 1886. Serial No. 220,067. (No model.) Patented in France February 16, 1883, No. 153,763; in England February 27, 1883, No. 1,060; in Belgium February 28, 1883, No. 60,477; in Italy March 31, 1883, No. 15,224, and in Austria-Hungary June 10, 1883, No. 10,691 and No. 25,373.

To all whom it may concern:

Be it known that I, FRIEDRICH VON MARTINI, a citizen of the Republic of Switzerland, residing at Frauenfeld, in Switzerland, aforesaid, have invented a new and useful Gas-Motor, (for which I have obtained patents in France, No. 153,763, bearing date February 16, 1883; in Great Britain, No. 1,060, bearing date February 27, 1883; in Belgium, No. 60,477, bearing date February 28, 1883; in Italy, No. 15,224, bearing date March 31, 1883, and in Austria-Hungary, No. 10,691 and No. 25,373, bearing date June 10, 1883,) of which the following is a specification.

In gas-engines with ordinary crank-motion and compression-chamber in which an ignition takes place after every second rotation of the crank-pin the suction-stroke is equal to the expansion stroke of the piston. In consequence of this arrangement the expanded gases are discharged with a tension of about two atmospheres.

The present construction has for an object to utilize the expansion as much as possible, and for this purpose the engine works with a specially-arranged compression-chamber and an ignition-chamber in such a manner that a suction and a compression take place during one rotation of the axle with a small piston-stroke, while a complete expansion occurs during the following revolution with large piston-stroke.

In the accompanying drawings, which illustrate the invention, Figure 1 is a longitudinal section; Fig. 2, a side view; Fig. 3, a front view, the crank-bearings in section; Fig. 4, a back view, and Fig. 5 a horizontal section in which the axle 17 serves as a fly-wheel shaft, while Fig. 6 shows a modified construction in which the fly-wheel is on the axle 15. Fig. 7 is a vertical cross-section on the line 12, Fig. 1. (In Figs. 1 to 7 the details of the compression-chamber are omitted for the sake of clearness.) Fig. 8 is a longitudinal section of the cylinder on a larger scale, showing the details of the compression-chamber, igniter, valve-gear, and governor. Fig. 9 is an enlarged part sec-

tional elevation of the cylinder, illustrating the governor; Fig. 10, a vertical section showing the igniting arrangement. Figs. 11 to 14 show various positions of the piston for the purpose of explaining the functions of the compression-chamber.

The compression-chamber 2 forms the continuation of the cylinder 1, and both are cooled with water, as usual. At the back wall of the compression-chamber are situated, side by side, the inlet-valve 51 and the ignition-valve 61, Figs. 4 and 5. The mixed air and gas flow into the cylinder 1 and its chamber 2 through a port, *r*, and the gases from the cylinder flow first from the chamber 2 into the mixing-chamber *m*, Fig. 8, and passing closely to the ignition-valve, Figs. 5 and 9, enter the compression-chamber through the orifice *n*, Fig. 8. The gases entering the latter are not free to expand over the whole space, but are guided and kept separate by tubes. They enter first the tube 49, Fig. 8, which is in closed by a tube, 48. Both tubes are fixed. Tube 48 has at its base several apertures, 50.

To the piston are attached two tubes, 45 and 46, adapted to move in the tubes 48 and 49 freely, but with as little clearance as possible. In Figs. 1 and 5 the tubes 48 and 49 are omitted, in order to avoid crowding. The tube 46 is provided near the piston with apertures 47. In consequence of this arrangement the entering gases are compelled to pass first through the internal tubes, 49 and 46, and then through the openings 47 into the outer tubes, 45 and 48, from which they escape through the apertures 50 before reaching the relatively-cooled cylinder-walls. The distribution of the gases will therefore take place as illustrated by Figs. 11 and 14. In Fig. 11 the piston begins its sucking action. All spaces are filled with gaseous products of combustion, and are of such a size that at the end of the suction-stroke these gases form a jacket for the explosive charge 90 which has been drawn in, as indicated by Figs. 11 to 14. The usual so-called "waste space" is purposely enlarged into the compression and separation chamber 2. The dotted vertical

lines in Fig. 11 indicate gases of combustion produced by the preceding operation, while the dotted lines running from the upper left-hand corner toward the lower right-hand corner represent a small quantity of air between the products of combustion and the explosive charge. The dotted lines running from the upper right-hand corner toward the lower left-hand corner represent the explosive charge, and the horizontally-dotted lines the products of the combustion which has just taken place. At the beginning of the stroke of the piston only a small quantity of atmospheric air is allowed to enter, and immediately afterward the full explosive charge. At the end of the suction-stroke, Fig. 12, all incombustible gases will have been displaced toward the cylinder-walls, while the combustible gases are strictly separated from the others inside the tubes. This separation remains unaltered at the close of the compression, at the beginning of the ignition, Fig. 13, and till the end of the expansion, Fig. 14. The object is to avoid a mixture of the gases. By this construction of the compression-chamber the following advantages are obtained:

First: An almost perfect separation of the charge from the other gases, as already mentioned.

Second. A successive combustion of the charge instead of an instantaneous explosion, the combustion being caused to proceed like a rocket along the tubes.

Third. As the combustion takes place only inside the tubes, the latter are heated to a high degree, and serve for the preliminary heating of the gases newly introduced.

Fourth. The heat produced by the explosion or combustion of the gases may be utilized by expansion, instead of being wasted by heating the cooling-water. Less cooling-water is required.

Fifth. The flame is prevented from touching the walls of the cylinder by the surrounding body of incombustible gas.

Sixth. The sliding parts of the piston move only in incombustible gases, in consequence of which less lubrication is required.

The driving mechanism connected with the piston consists cinematically of an isosceles rotating double crank, the small crank 16, Figs. 1, 2, 5, 6, 8, serving to turn the shaft 17, while the large crank 14 drives the shaft 15. The two cranks 14 and 16 are connected by the arm 13, the length of which equals the radius of the larger crank, 14. The distance between the bearings of the two cranks equals the radius of the smaller crank, 16. In this mechanism the small crank 16 makes two revolutions, while the large crank 14 makes only one.

The novelty of the present construction consists in making a point (a transverse part or crank-pin) of the coupling-rod 13 or link the center of the driving-pin of the piston-rod 8. This point 36, Figs. 5 and 8, describes a curve

called "lemniscoid," which in this case closely resembles two unequal circles joined together at one point on the peripheries and placed eccentrically one inside the other. These circles, being alternately described by the driving-pin, may serve to determine alternately a long and a short stroke of the piston. The ratio of the diameters of these two circles depends on the position of the point 36 on the coupling-rod 13. In Fig. 8 this lemniscoid is shown in dotted lines. The nearly-circular portion *fgh* corresponds to the suction-stroke, *hfi* to the compression-stroke, *ik* to the expansion-stroke, and *kf* to the discharge or exhaust stroke. The rod 8 connects the pin 36 with the piston 7. The lemniscoidal motion of the driving-pin is also applicable to engines without separate compressing-chambers, in which engines the gases of combustion are completely discharged from the cylinder after the expansion and the compression have been obtained by altering the stroke of the piston. In the present construction the stroke may be altered by placing the axis of the cylinder at various angles to the line connecting the two crank-centers 17 and 15 of the cranks 14 and 16, Figs. 5 and 8. If, for instance, in Fig. 8 the cylinder is placed at B, in the direction of B' B', the line *a'a'* corresponds to the suction-stroke, and *a'b* to the compression-stroke, the compression-chamber being formed by the difference of the strokes represented by the line *ab*. The curve *ba* would correspond to the exhaust-stroke. By the choice of the point 36 on 13, as well as by the choice of the position of the cylinder-axis B' B', the ratios between suction, compression, and expansion strokes may be varied within wide limits. In the examples shown by the drawings the lemniscoid is not situated symmetrically to the axis of the cylinder, but so that at the end of the compression the power-piston has entered the cylinder a little farther than at the end of the exhaust stroke. The object of this unsymmetrical position is to automatically produce the ignition of the charge by the stroke of the piston. The igniting apparatus is illustrated by Figs. 8 to 10. It consists of a conical valve, 62, with cylindrical extension 64 and piston-valve 61. The latter moves tightly in the cylinder 80, to which the permanently-burning igniting-flame 60 has access through the port 81. The flame 60 is protected by the hood 59. The cylindrical extension below the ignition-valve enters with slight clearance a cylindrical bore below the seat of the ignition-valve. At the end of the compression-stroke a part of the piston, as a protuberance or finger, *v*, of the pipe 45, attached to the piston, strikes the lever 63 and opens the ignition-valve. The compressed explosive gases enter the cylinder 80 from the main cylinder with low tension, owing to their having been throttled by the cylindrical extension 64, and are ignited by the flame 60. As soon as the flame has struck into the chamber of the ignition-valve the

piston 61 closes the slot 81 and the ignition valve opens entirely, after which the ignition takes place in the compression-chamber.

It will be seen that all the operating parts 5 of the igniting apparatus are arranged within the cylinder and operated from the piston. By this arrangement, applicable to engines and igniters of various constructions, I avoid the objections incident to extending rods and parts 10 through packed openings in the cylinder to the outside thereof.

The motion of the inlet and of the discharge valve is effected from a point, 41, of the connecting-rod 8, Figs. 1 and 8. The discharge-valve 11 is below the compression-chamber in an intermediate piece, 3, of the hollow standard W, situated between the compression-chamber and the blow-off pot 4. The spent gases pass directly from 2 through 3 into 4, as 20 shown in Fig. 7.

On the valve-spindle s, which extends down into the blow-off pot, is fixed a disk, 70, Figs. 7 and 8, serving to open the valve. This valve is kept closed by a weight or spring, 12, Figs. 25 1 and 7. The point 41 of the connecting-rod 8 is connected with two parallel levers, 10 and 10, by means of a rod, 9. These levers have their fulcrum at 42 of a bracket on the piece 3, containing the outlet-valve, Figs. 1 and 8. 30 The point 41 describes a curve corresponding to the lemniscoid, but consisting of two nearly elliptical curves, d' t c' d, joined together, the travel during the exhaust period (in the direction indicated by an arrow) being from d to d'. 35 This part of the curve being the highest, the levers 10 are lifted up to their highest position. A cross-piece, 20, between these levers, Figs. 7 and 8, which comes in contact with the disk 70 of the valve rod s, controls the opening 40 and closing of the discharge-valve. The proportions of 10 and 9 and the position of the point 41 are such that the discharge valve remains closed while the point 41 passes through the other portions of its travel. The inlet-valve 45 51, constructed as a mixing-valve, is also controlled by an extension of one of the levers 10, beyond 42, from a point, 75, situated directly under the air-inlet 54, Fig. 8. The air-suction valve 51 is combined with a gas-inlet 50 valve, 56, and a stop-cock, 53, Figs. 2, 4, and 5. In Figs. 8 and 9 the gas-inlet valve is drawn in a different position in the same vertical plane as the valve 51, for the sake of clearness. After the stop-cock has been opened 55 the gas flows through the conduit 58 to the gas-inlet valve 56, and then into the annular space 52, from which small holes 55 lead to the seat of the valve 51. Consequently, when this valve is closed, air and gas are simultaneously 60 shut off. By opening the valve 51 while the gas-valve 56 is closed air alone is drawn in, and if the valve 56 is open an explosive mixture of gas and air, which are then more completely mixed in the mixing-chamber m. The 65 action of the valve-gear on the inlet-valve takes place during the admission period, dur-

ing which the point 41 of the connecting-rod 8 moves from d' to t, thereby lifting the point 75 of the rod 10, and causing the arm 25 to act on the valve 51, Fig. 8, so as to open the same 70 when required. To prevent the inlet-valve 51 from being further opened during the expansion period corresponding to the curve c' d, an oscillating motion in a vertical plane is also imparted to the arm 25 by means of an 75 eccentric, 21, mounted on the valve-gear shaft 15. This eccentric is connected with the arm 25 by means of rods 22 and 24, lever 23, and hinge-joint 26, and it is set at such an angle that during the suction-stroke the arm 25 remains nearly vertical, while during the other 80 periods the arm 25 moves sidewise to the left, and therefore the inlet-valve remains closed when the point 75 occupies its highest position, Fig. 9.

The regulation of the speed is effected by means of a pendulum, 27, having its fulcrum in 29. The period of oscillation may be altered by shifting the weight 28.

The pendulum receives motion from the laterally-swinging arm 25, which may have at 26 a roller adapted to come in contact during its oscillation with the adjustable face, y of the pendulum, Figs. 8 and 9, so as to impart to the same a speed depending also on the position of the face y. As the point 26 recedes rapidly, the pendulum is allowed to fall freely, thereby meeting, with a button, 57, thereon, the head z of the gas-inlet valve 56, so as to open the same, as shown in Fig. 8, and to control the explosive charge of the engine. As with equal angles of oscillation the periods of oscillation remain the same, the engine will always receive an equal charge during its normal action. In the drawings, Fig. 9, x represents the highest position of the pendulum with normal speed of engine. If, now, the speed of the engine increases, the following circumstances operate to retard the gas-inlet. The pendulum is acted upon more rapidly by 100 26, whereby the angle of oscillation increases (see dotted line x', Fig. 9,) and the pendulum begins its receding motion later. With the oscillating angle increases also the period of oscillation. Consequently, the engine is charged 105 later, and therefore with a smaller quantity of explosive gas. With slower oscillations the effects are the reverse of those just mentioned.

By suitably adjusting the period of oscillation the engine may be charged with explosive mixture during the whole of its suction-stroke, in order to obtain the maximum power. If less power is required, more or less air is first admitted before the explosive charge begins to enter, and, owing to the peculiar construction of the compression-chamber, these charges are kept separate as much as possible.

The construction of the engine may easily be modified, so as to draw back hot gases of combustion from the blow-off pot, when the 130 speed of the engine is too great, instead of admitting cold air, until the explosive charge

commences to enter, for which purpose the exhaust-valve must be adapted to perform the function of a suction-valve, and the opening of the air and of the gas-inlet valve must be effected simultaneously by the governor. The engine-stand 4 serves, also, as a blow-off pot, and the stand 6 serves as a gas-reservoir, and may be provided with a gas-pressure regulator.

10 Instead of the valves described, slide-valves may be employed and set in motion from the shaft 15, which makes only one-half of the number of revolutions of the shaft 17.

As an advantage of the lemniscoid motion 15 may be mentioned that the piston possesses the greatest speed during the period of expansion, because the pin 36 travels through the two lemniscoidal circles in equal periods.

I do not limit myself to the exact details 20 shown by the drawings, as the same may be altered without departing from my invention.

I claim—

1. In gas engines, a compression-chamber, 2, containing fixed tubes, and movable tubes 25 attached to the power-piston, the said tubes being open at outer ends, with intervening spaces, and adapted to slide in each other, and constructed or arranged substantially as described, for the purpose of keeping the gases 30 within the tubes and separate.

2. A gas-engine provided with a cylinder, piston, crank-shaft, and connecting-rod, and a crank-pin and connections therewith, whereby a lemniscoidal motion is imparted to said 35 crank-pin, whereby a variable motion is given to the piston, substantially as and for the purpose set forth.

3. The combination, with the piston and connecting-rod of an engine, of two crank-shafts 40 and an intermediate crank-link to the crank-pin of which the connecting-rod is attached, all arranged to permit two revolutions of one shaft to each revolution of the other, substantially as and for the purpose set forth.

45 4. The combination of the inlet and outlet valves, the connecting-rod 8, means to guide it to carry a pawl, 41, thereon in a lemniscoid, and connecting mechanism adapted to open the inlet and outlet valves according to the 50 elevation of the point 41 on the said rod, substantially as described.

5. The igniting apparatus consisting, essentially, of the conical valve, the cylindrical throttle-valve, and piston-valve, and mechanism 55 for operating the same set in motion by the power-piston of the engine, the whole combined and adapted to operate substantially as described.

6. The combination, with the power-cylinder 60 of a gas-engine, of a chamber having a port extending to the flame and a port extending to the cylinder, and valves adapted to

each port, and valve-operating contrivances, whereby the cylinder-port is positively opened while the gas-port is opened and the latter 65 then closed by the positive movement of its valve, substantially as and for the purpose set forth.

7. The combination of the chamber having two ports—one leading to the chamber in the power-cylinder and the other to the igniting-flame—and valves closing said ports and connected rigidly to the same stem to permit the cylinder-port to be opened and the gas-port to be closed by one movement of the valve, substantially as and for the purpose set forth. 75

8. The combination, with the igniting means of a gas-engine, of a lever arranged to be operated inside of the cylinder from the piston, substantially as and for the purpose set forth. 85

9. The combination of the cylinder and piston of a gas-engine and an igniting device provided with an operating-lever arranged within the cylinder to be moved by the piston to ignite the charge, substantially as and for the purpose set forth. 85

10. The combination, with the cylinder and piston of a gas-engine, of an igniting device provided with a lever arranged within the cylinder and a finger carried by the piston to make contact with and move the lever to explode the charge, substantially as described. 90

11. The combination, with the cylinder and piston of a gas-engine, of an igniting device provided with a movable portion arranged to be operated by the contact of the piston, substantially as described. 95

12. In a gas-engine, a cylinder, piston carrying a finger, and a lever from the movement of which the charge is ignited, hung within the cylinder to make contact with said finger as the piston completes its rear stroke, substantially as described. 100

13. In a gas-engine, a piston provided with a finger for operating the igniting device, substantially as described. 105

14. In a gas-engine, the igniting device arranged within the cylinder to make contact with and be operated by the piston, substantially as described. 110

15. A pendulum-governor made adjustable by moving a weight and adapted to be lifted more or less by mechanism substantially as shown, according to the intensity of periodical impulses, depending on the speed of the engine, so as to open a gas-inlet valve sooner or later by coming in contact with the valve or its connection sooner or later, substantially as described. 115
